5 screw arranged in said frame for projection and retraction therefrom, an operating member arranged in said frame and having co-operative engagement with said lifting screw to move the same in the frame, and a one-piece spring surrounding and carried by the lower end of the lifting screw and normally yieldingly urged to frictionally engage the lifting screw and having keyed connection
10 with the frame whereby to normally prevent relative rotation with respect to the frame while permitting the lifting screw to move longitudinally.

17. A lifting jack comprising a hollow standard having a non-circular inner bore, and having a rotatable driving member, a threaded sleeve projectable by said driving member, a coil of spring wire embracing the lower end of said sleeve, said coil having portions engaging with a non-circular portion of the bore to prevent normal rotation of the sleeve in the bore, said coil forming a yielding connection between the sleeve and the standard whereby to permit the sleeve to rotate
25 with the driving member.

18. In a double screw lifting jack, in combination, a standard provided with a longitudinal opening and provided with a longitudinal guideway, an interiorly threaded nut
30 mounted in the upper portion of said standard, means for rotating said nut, a tubular sleeve mounted in said standard and provided with an exterior thread and at its upper end with an interior thread, the lower portion
35 of said tubular sleeve having a relatively smooth portion, a coiled spring frictionally gripping the smooth portion, a free end of said coiled spring engaging said guideway, the bottom of the tubular sleeve having means
40 preventing the inadvertent detachment of the coiled spring, and a second screw threaded member having exterior threads engaging the interior threads of the tubular sleeve.

In testimony whereof I hereto affix my
45 signature.

WILLIAM B. RUNYAN.

UNITED STATES PATENT OFFICE

FRED F. RUSSELL, OF OAKLAND, CALIFORNIA

CLUTCH

Application filed April 17, 1930. Serial No. 445,171.

The present invention seeks to provide a clutch which will operate efficiently, will be composed of few moving parts and may be easily manipulated. One embodiment of the invention is illustrated in the accompanying drawings, and the invention resides in certain novel features which will be hereinafter first fully described and then more particularly defined in the appended claims.

10 In the drawings:

Figure 1 is a longitudinal section through a clutch embodying the invention,

Fig. 2 is a view, partly in transverse section and partly in side elevation, the broken line 1—1 in this figure indicating the plane of the section shown in Fig. 1,

Fig. 3 is a detail sectional elevation illustrating the action of the dogs in applying the shoes to the drum,

20 Fig. 4 is a side elevation of the sliding cam,

Fig. 5 is an enlarged detail section showing the yieldable means for retracting the shoes from the drum, and

25 Fig. 6 is a detail perspective view of one of the dogs.

Referring to the drawings more particularly by reference numerals, the numeral 1 denotes a portion of the casing surrounding 30 the clutch which casing may be of any convenient or approved form and is equipped with a detachable cover 2 at one end. The driving shaft is indicated at 3 and to the end of said shaft is secured a drum or pulley 4 having an overhanging rim 5. A socket or bearing opening, indicated at 6, is formed at the center of the drum and in the end of the driving shaft to receive the reduced end 7 of the driven shaft 8, bearing rollers 9 being 40 disposed around the reduced end of the driven shaft so as to reduce the frictional wear. The driven shaft extends through and beyond the cover 2 and, within the casing, its end is provided with longitudinal 45 keyways or grooves 10 to receive a hub 11 so that the hub will be held upon the shaft and caused to rotate therewith. A set screw 50 is mounted radially in the hub and engages the shaft to bind the hub thereon, the set screw being secured in place by a spring

locking ring 51 or other locking device. The hub 11 forms the center of a disk 12 which has its periphery disposed close to the inner circumference of the rim 5 and which is constructed at intervals with openings or radial 55 slots 13 and peripheral notches 14. The shoes 15 are disposed about the periphery of the disk 12 and are formed between but at unequal distances from their ends with lugs 16 which engage in the respective notches 14 and are slightly rounded upon their end edges, as shown at 17, whereby they may have a slight rocking movement within the notches, the inner ends of the lugs being 60 plane, as will be understood upon reference to Figs. 2 and 3. Adjacent their ends the shoes are provided with pairs of inwardly 65 extending radial lugs 18, the members of each pair extending on opposite sides of the disk 12, as clearly shown in Fig. 1, and engaged through the openings 13 and the inner ends 70 of these lugs are the terminals 19 of torsion springs 20 which have their intermediate 75 portions coiled around stud bolts 21 mounted in the disk between the cooperating pairs of lugs, as shown in Figs. 2 and 5, washers 22 and 23 being provided upon the bolts at the 80 sides of the coils, as shown in Fig. 5, so as to retain the coils in proper position upon the bolts and obtain the proper purchase for the head of the bolt to properly anchor the springs on the side of the disk presented to the drum. The terminals 19 of these springs pass through the slots 13 in the disk and are 85 thereby permitted to play radially to a sufficient degree to accommodate the necessary movement of the shoes in opening or closing the clutch.

Disposed within each notch 14 between the base of the notch and the lug 16 is a dog 24 which has flat sides and is also equipped with annular flanges 25 at its ends which engage against the opposite faces of the disk and the lug 16 whereby to resist endwise movement 90 of the dog and maintain it in its proper relation to the disk and the lug of the shoe. Extending from one end of the dog is a lever or 95 rocking arm 26 which is equipped at its free end with a roller 27 arranged to engage and move on the opening and closing cam. The 100
